UNITED STATES PATENT OFFICE.

GEORGE TIEMANN, OF BROOKLYN, NEW YORK.

IMPROVEMENT IN FASTENINGS FOR SURGICAL INSTRUMENTS.

Specification forming part of Letters Patent No. 41,243, dated January 12, 1864.

To all whom it may concern:

Be it known that I, GEORGE TIEMANN, of the city of Brooklyn, in the county of Kings and State of New York, have invented, made, and applied to use a certain new and useful Improvement in Means for Holding Surgical Instruments, &c., when Opened Out of their Handles; and I do hereby declare the following to be a full, clear, and exact description of the same, reference being had to the annexed drawings, making part of this specification, wherein—

Figure 1 is a side view, and Fig. 2 is an edge view, of a surgical instrument with my improvement attached.

Similar marks of reference indicate the same parts.

Knives and various kinds of instruments, particularly surgical, have been fitted into handles and provided with spring-catches and small slides to hold the instrument open and rigidly projecting from the handle, in order that such instrument may not shut up or close into the handle while in use. The spring-catches are not reliable, and are of such a character generally as to injure the nails of the fingers or thumb when releasing the spring for the instrument to be closed, and the slides generally have passed through slots in the handle, and have hence rendered the handle liable to break. This is particularly the case with small surgical instruments.

The nature of my said invention consists in a turning fastener or button applied to the heel or shank of the instrument, and taking over the edge of the handle, so as to fasten the instrument in position when open.

In the drawings, *aa* are the side pieces forming the handle, in which one or more knives, surgical or other instruments are fitted to open

or shut by turning upon a cross-pin, *b*, as usual. The instrument itself is represented at *c*, and is provided with a stop at *d*, formed of small flanges that take upon the edges of the handle when the instrument is open. These stops are well known.

e is my turning fastener or button, made of a small piece of metal with a hole through it, by which it is to be attached to the instrument by a screw or pin, and I prefer that the same be introduced below an overhanging flange formed in the shank of the instrument. The width of this button is to be such that it will pass between the sides of the handle when parallel with the instrument; but when turned across will take over the edge or edges of the handle, and thereby retain the instrument in an open position.

This improved instrument-fastener may be formed as a button extending on both sides of the attaching pin or screw.

The advantages of this device will be apparent from the foregoing. The handle is not weakened, there is no opportunity for obstruction by dirt, and the button can freely be turned in either opening or closing the instrument.

What I claim, and desire to secure by Letters Patent, is—

The turning fastener or button applied to surgical or other instruments to retain them in position when opened out of a handle, as and for the purposes specified.

In witness whereof I have hereunto set my signature this 23d day of November, 1863.

GEO. TIEMANN.
